OF CHICAGO, ILLINOIS, A CORPORATION OF MAINE.

PROCESS FOR INCREASING THE PRODUCTION OF OIL-WELLS.

1,099,170.

Specification of Letters Patent. Patented June 9, 1914.

Application filed December 12, 1913. Serial No. 806,269.

To all whom it may concern:

Be it known that I, IRWIN L. DUNN, a citizen of the United States, residing at Marietta, in the county of Washington and State 5 of Ohio, have invented certain new and useful Improvements in Processes for Increasing the Production of Oil-WellS, of which the following is a specification.

It is well known that petroleum is ordinarily found at considerable depth in strata of porous stone or sand which is overlaid by impervious strata. The oil bearing stratum may be of greater or less extent but it is inclosed at its sides or edges by impervious walls so that it is, in effect, in a hermetically sealed chamber or dome which it fills or substantially fills. Ordinarily, oil is not the only fluid occupying the pervious rock or sand but it is usually or always accompanied by gas and, not infrequently, by water, the three fluids arranging themselves as appears from observations by oil operators, according to their respective specific gravities, the water occupying the lower layers of the stratum, the oil being supernatant upon the water, and occupying the middle portion, and the gas occupying the upper portion of the stratum. The gas is usually under considerable pressure and when such 30 a bed or stratum of sand containing oil is pierced by a well, oil flows into the well and at first is driven out by the pressure of the gas behind it. The gas escapes with the oil, however, and after a time the pressure and 35 the flow of oil diminish or cease and resort is had to torpedoing the well which temporarily increases its production. Finally the well must be pumped by an ordinary mechanical pump to further draw off 40 the supply of oil. In many cases even this resource has failed and the wells been abandoned, even though, as has been shown, the rock still contains large quantities of oil which is probably held therein by capillarity. 45 Various methods have been proposed to increase or renew the productiveness of wells whose output has fallen low or ceased, among others that of substituting for the exhausted natural gas in the rock above the 50 oil compressed air or other artificially supplied pressure medium. This has been accomplished with satisfactory results in many cases either by supplying the gas or air directly to the well to be pumped, relieving the pressure at the well during the 55 only at the outlet well but through the 60 65 70 75 80 85 90 95 100 105 110

pumping operation or by introducing the pressure at a well or bore more or less remote from the well or wells to be pumped and continuously applying the pressure. In either case the compressed air or other gas is forced in for a considerable period of time which may be weeks or months so that ultimately the top of the chamber inclosing the porous rock or sand contains a cushion of compressed gas acting upon the oil in the rock beneath it. When the air or gas is introduced into one of a number of wells it, of course, spreads in all directions throughout the porous rock, mainly, however, in the dry rock above the oil, if any such exist, and tends to and does flow through the rock to the neighboring wells driving and carrying with it the petroleum which has been held by capillary action in the rock. In many cases very satisfactory results have been obtained by this process. In other cases, however, the results have not been quite so satisfactory and it is for the purpose of improving the results in such cases that my present invention was devised, though it is also of advantage where reasonably satisfactory oil production has been attained by the process just described. The reason for the great success of the process as thus far described, in some instances and its partial failure in others, owing to the conditions of operation can perhaps never be determined with certainty, but the phenomena which I have observed seem to indicate that the pressure medium, in those cases where inferior results have been obtained, finds a comparatively easy path from the well at which it is introduced to the wells from which the oil is to be pumped either over the oil in the upper dry levels of the rock or through some other course, so that it does not penetrate the layers containing the oil at all or to a satisfactory degree, or produce sufficient pressure thereon to drive the oil out of the rock. Acting upon this theory of the imperfect action of such wells, instead of permitting the gas or air to go free at the outlet wells or wells being pumped, I maintain a counterpressure upon the latter which, however, is materially less than the pressure at which the gas is forced in and therefore not sufficient to prevent flow of air through the rock. It is sufficient, however, to maintain a material pressure not only at the outlet well but through the 60 65 70 75 80 85 90 95 100 105 110

rock. Ordinarily, I have found that my invention works satisfactorily when a pressure of say ten pounds above the atmospheric pressure is maintained at the outlet well and the compressed air or other gas is introduced at the inlet well at a pressure of about forty pounds. By operating in this manner, the oil rock is maintained under a pressure in excess of ten pounds and yet is under a differential of thirty pounds, forcing the air from the inlet well to the outlet well.

It will be apparent from what has been said that my process may be practised where there are but two bores, or even, in that form thereof in which the pressure is introduced at the same well from which the oil is withdrawn with a single well. Ordinarily, however, the properties to which my process is applied will comprise a number of wells, in which event, I ordinarily choose one of them near the center of the group for the introduction of the air reserving the others for pumping out the oil. Obviously also if for any reason I do not pump all the wells, those not used and any other avenues for the escape of air should be plugged in some suitable manner to prevent the escape of air therethrough.

In the accompanying drawing, I have illustrated diagrammatically my system as applied to two oil wells, though it will be understood that it is not limited thereto but that any number of outlet wells may be employed in connection with a single inlet well, as stated above, and that the nature of the apparatus employed for carrying out my process and the process itself may vary in many respects. The specific disclosure, therefore, is for the purpose of exemplification only and the invention is defined in the following claims in which I have endeavored to distinguish it from the prior art, so far as known to me without, however, relinquishing or abandoning any part or feature thereof.

The accompanying drawing represents a section through a body of land containing two wells equipped for the practice of my process, the plane of section being central of the two wells.

As a preliminary to practising my process one of the wells A is closed or capped at the top or at some convenient point and an air supply pipe B extends through the seal and to an air compressor C capable of supplying air in considerable quantities preferably at a pressure in excess of forty pounds to the square inch. Preferably the well is cased to such a point that escape of the air around the same is entirely prevented and it is all forced into the rock or sand. The outlet wells, affected by the introduction of the air, and represented in the drawing at D, are located at different distances from the inlet

well, depending largely on the character and perviousness of the stratum in which the oil is found. Thus where it is very pervious the wells may be located at greater distances than are possible where the rock is very close and but slightly pervious. The outlet well D is also preferably cased where it is necessary to prevent the escape of gas or air and closed as at E about the pump tube H which latter may be of any suitable character. The pump tube H, however, is closed at the top and packed about the pump rod J and from a suitable point, preferably near the top of the casing, a pipe K leads to a pressure regulating device shown conventionally at L in the drawing. This pressure regulating device may be of any suitable or approved character, being shown as an ordinary weighted valve, and is ordinarily set to maintain a pressure of about ten pounds. As long as that pressure is exceeded in the well the gas or air is permitted to escape so that there is a continuous flow from the inlet well to the outlet well. There is thus maintained along with the flow of the air or gas a continuous pressure of more than ten pounds in excess of atmospheric pressure which seems to cause the air to penetrate into the oil laden pores and interstices of the oil rock and to drive the air therefrom and into the outlet wells from which it may be pumped.

Instead of permitting the air to directly escape from the outlet wells, as described above, being saturated or heavily laden with gasolene and lighter hydro-carbons, it may be used as fuel or passed through condensers by which the gasolene and other valuable constituents may be squeezed out of it.

The foregoing description of the operation of my improved process is based upon and includes the theory of operation thereof which seems most probable to me, but whether or not the theory be correct I have found that by applying back pressure as described in the operation of the process, most satisfactory results have been obtained where without such back pressure the increase of production due to the process has been relatively small in some instances.

I claim:

1. A process for increasing the production of oil wells consisting in forcing gas under pressure into the oil bearing rock, permitting it to flow from the rock under a back pressure and gathering the oil released thereby.
2. A process for increasing the productivity of a group of oil wells consisting in forcing a pressure medium in at one of the wells maintaining it under regulated pressure at the other wells and pumping off the oil from the latter.
3. A process for increasing the productivity of oil wells consisting in sealing the

wells and other outlets from the oil rock, forcing compressed gas in at one of the wells and permitting it to escape at one or more of the other wells under back pressure.

5 4. A process for increasing the productivity of oil wells consisting in sealing the wells and other outlets from the oil rock, forcing compressed gas in at one of the wells at a pressure of about forty pounds 20 and permitting it to escape at one or more of the other wells under a regulated back pressure.

10 5. A process for increasing the productivity of oil wells consisting in sealing the wells and other outlets from the oil rock, 15

forcing compressed gas in at one of the wells at a pressure of about ten pounds and permitting it to escape at one or more of the other wells under a regulated back pressure.

6. A system for the production of oil comprising a pair of bores or wells sealed against egress of air, a compressor connected to one of the wells and an oil pump and pressure regulator connected to the other well.
